UNITED STATES PATENT OFFICE.

HENRY W. BEHRENS, OF CHICAGO, ILLINOIS.

PRICE-TAG HOLDER.

1,341,491.

Specification of Letters Patent. Patented May 25, 1920.

Application filed September 3, 1918. Serial No. 252,460.

To all whom it may concern:

Be it known that I, HENRY W. BEHRENS, a citizen of the United States, residing at Chicago, in the county of Cook and State 5 of Illinois, have invented certain new and useful Improvements in Price-Tag Holders, of which the following is a specification.

This invention relates to tag holders, and more particularly to price tag holders for 10 shelves.

The main object of the invention is to provide simple and efficient devices of this character which are cheap to manufacture and may be quickly applied and removed 15 without in any way marring the shelf or other support to which it is attached.

Another object is to provide holders of this character constructed so that the tags may be easily inserted and removed without 20 disturbing the holder.

With the foregoing and other objects in view, which will appear as the description proceeds, the invention resides in the combination and arrangement of parts and in 25 the details of construction hereinafter described and claimed, it being understood that changes in the precise embodiment of the invention herein disclosed may be made within the scope of what is claimed without departing from the spirit of the invention.

In the accompanying drawings:—

Figure 1 represents a front elevation of a portion of a shelf showing one form of 35 this improved tag holder applied.

Fig. 2 is a transverse vertical section taken on the line 2—2 of Fig. 1,

Fig. 3 is a horizontal section taken on the line 3—3 of Fig. 1.

40 In the embodiment illustrated, the holder constituting this invention comprises a tag receiver in the form of a plate 1 having in-turned flanges 2 at its opposite ends spaced from the body of the plate a sufficient distance to permit the easy insertion and removal of a tag T. The lower edge of this

plate is provided with longitudinally spaced forwardly extending lugs 3, which project a sufficient distance to support the lower edge of the tag T and yet not be visible when 50 viewed from the front.

Extending rearwardly from plate 1 are two shelf engaging elements 4 and 5 in the form of tongues which are designed to be engaged with the opposed faces of the shelf 55 S and clamp the holder in operative position. The upper element 4 is in the form of a plate and extends at right angles from plate 1, being rectilinear throughout its length, while the lower element 5 is also 60 in the form of a plate, but is curved inwardly longitudinally with its free end flared as shown clearly in Fig. 2 to adapt it to clamp the shelf and provide for its attachment to shelves of varying widths. 65

The foregoing description and the drawings have reference to what may be considered the preferred or approved form of my invention. It is to be understood that I may make such changes in construction 70 and arrangement and combination of parts, materials, dimensions, etc., as may prove expedient and fall within the scope of the claimed invention.

Having thus fully described my invention, 75 what I claim as new and desire to secure by Letters Patent, is:—

A tag holder comprising a metal plate having tongues extended rearwardly from its side edges to form support engaging 80 clips, one of said tongues being flat and extended at right-angles to the plate and the other being bent out at a slight angle to enable the device to be readily secured to shelves of varying thickness, the front face 85 of said plate having tag retaining means.

In testimony whereof I affix my signature in presence of two witnesses.

HENRY W. BEHRENS.
